CURRENT DIVERSION MEANS

Leonard E. Fisk and Leroy E. Lucas, Topeka,
Kans.

Application October 29, 1936, Serial No. 108,134

4 Claims. (Cl. 61—3)

This invention relates to improvements in current diversion means for use in the control of stream flow.

The object of this invention is to provide a means for current diversion comprising the installation of a plurality of anchored obstacles in a manner arranged to reduce the velocity of stream flow and function to prevent erosion of banks and to induce the deposit of silt to further 10 protect and repair the boundaries of a river.

These and other objects will hereinafter be more fully explained.

Referring to the drawing in which like characters apply to like parts in the different views: 15 The figure on the drawing is a schematic plan view illustrating the manner in which several strings of obstacles of a permeable nature are installed to protect and repair the condition of bank erosion shown.

20 The drawing illustrates a schematic plan view of the installation of several strings of obstacles of a permeable nature so placed that they will prevent further destruction of the confines of a stream at a highway crossing.

25 The highway 9 crosses the stream 10 over the bridge 11.

The flow of the stream 10 as indicated by the arrows has eroded the bank 12 from a point beginning at C to the point D adjacent the bridge 30 abutment. The bank is destroyed in the shape of a semicircular cut to the extent of E. The removal of the bank by erosion has approached the highway 9 and threatens the destruction of the highway grade at F. This situation has been in 35 evidence in many places along the bank of ordinarily slow velocity streams having comparatively low banks and broad water courses. The present trend of modern highway construction with costly road surfacing and grading justifies the proper 40 maintenance of the banks of adjacent streams. This invention provides a remedy for the condition illustrated by the installation of several strings of obstacles in the following manner:

A string or line of spaced obstacles 13 having 45 the upstream end firmly anchored in the bank 12 near the point C and with the downstream end terminating near the point D. This string is designated as the main deflector and provides the main line of diversion. This and other strings 50 are indicated on the drawing by a line drawn through a series of dots or circles which represents the obstacles. Although the obstacles are preferably those of a permeable nature other types 55 may be used either of a fabricated steel design or

a series of pile jetties set in the bed of the stream in a similar line.

A plurality of strings of spaced obstacles 14 and 15, installed approximately parallel to the main deflector and at a distance upstream from the latter and spaced from each other in the direction of the stream flow, the line of each being at an angle to the stream flow. These are designated as primary deflectors and provide protection for the upstream end of the main line of diversion. In some instances the flow of the stream is such that the primary deflectors are not required.

A plurality of strings of spaced obstacles 16 and 17 installed normal to the flow of the stream with in the area C—E—D are anchored to the bank at one end between C and E and at the other end are each connected to the main deflector at G and H respectively. These are designated as secondary deflectors and provide further retardation or 20 back-up of the main line of diversion.

The primary deflectors 14 and 15 serve to protect the bank adjacent to the point at C and reduce the velocity of the stream flow at the upstream portion of the main deflector 13.

The main deflector 13 reduces the stream velocity along the line of the original bank and serves as a base line for silt deposit for the new bank line.

The secondary deflectors 16 and 17 reduce still 30 further the velocity of the stream within the area C—E—D and also reduce the backwash from the bank between E and D and function to build up and maintain a silt deposit.

The obstacles herein described and the manner in which they are installed provide an effective and economical means of controlling stream flow velocities and serve to protect and repair the condition of bank erosion illustrated and what we claim as new and desire to secure by Letters Patent is:

1. In a main line and back up diversion of stream flow, a string of structural obstacles, said string positioned in the bed of a stream on the chord of an eroded arc in the bank, two or more 45 additional strings of structural obstacles, said strings positioned on the bed of the stream and spaced from each other within the area of the eroded arc, one end of each fastened in the bank and the other end of each connected to the first 50 said string.

2. In a system of permeable obstacles in the bed of a stream, a plurality of obstacles connected to a cable comprising a string, a main deflector string positioned across the mouth of an eroded 55

area, a plurality of secondary deflector strings positioned within the eroded area and spaced from each other, a plurality of primary deflector strings spaced from each other and positioned near the upstream end of the main deflector string.

3. In a bank protective installation, a line of permeable jetties across the mouth of an eroded area, other lines of permeable jetties positioned

within the area and spaced from each other and at an angle to the first said line.

4. A current diversion means, a means comprising a line of jetties extending substantially across the mouth of an eroded area, and a line of jetties extending from the first said line at an angle thereto and extending within the eroded area. 5
